(57) **CLAIM**

The ornamental design for a crane remote control device, as is shown and described.

DESCRIPTION

The patent or application file contains at least one drawing executed in color. Copies of this patent or patent application publication with color drawing(s) will be provided by the Office upon request and payment of the necessary fee.

FIG. 1 is a top perspective view of a crane remote control device, as claimed herein;

FIG. 2 is a bottom perspective view thereof;

FIG. 3 is an alternative bottom perspective view thereof;

FIG. 4 is a top view thereof;

FIG. 5 is a bottom view thereof;

FIG. 6 is a left view thereof;

FIG. 7 is a right view thereof;

FIG. 8 is a front view thereof; and,

FIG. 9 is a back view thereof.

The dashed lines shown depict the environment and represent unclaimed subject matter and form no part of the claimed design.
